AUTOMATIC SELECTIVE RECORD CHANGER

Lloyd J. Andres, Chicago, Ill., and Theodore M. Wright, North Tonawanda, N. Y., assignors to Automatic Instrument Company, Grand Rapids, Mich., a corporation of Michigan

Application January 28, 1938, Serial No. 187,500

3 Claims. (Cl. 274—10)

This invention relates in general to improvements in automatic phonographs, and more particularly to an automatic phonograph mechanism adapted to play one or more selected records automatically without attention of the operator after the selection is made.

The principal object of this invention is to provide a simplified compact machine capable of playing one or more selected records, and following the playing of each record, restoring said record or records to their respective storage positions, without manual operation.

A further object of the mechanism is the provision for a vertically movable record magazine containing an individual shelf for each record, said shelves inherently protecting the records from breakage and warping.

A further object of the invention provides for two pivotally mounted arms arranged to swing horizontally for the purpose of sliding a selected record from its shelf in the record magazine onto the turntable for playing, and upon the completion of playing, returning the record from the turntable to its shelf in the record magazine.

A further object of this invention provides for the automatic withdrawal of the turntable spindle during the time the record is being slid from its shelf onto the turntable, and subsequently projecting the turntable spindle through the central hole of the record for playing; and after playing the record, again withdrawing the turntable spindle, permitting the record to be slid from the turntable back to its original position on its respective shelf.

A further object of this invention provides for the utilization of a new selector system utilizing a combination of mechanical and electrical elements cooperating to select and play the selected records, and subsequent to the selecting of each record, automatically restoring the corresponding selector elements to their normal positions; and upon the completion of the play of all selected records, opening a master switch, bringing the entire machine to its rest position.

Another object of this invention provides for the use of one driving motor for operating both the record changing mechanism and the turntable; including means for stopping the turntable during the period a record is being transferred.

Another object of this invention is the provision for a positively driven means for raising and lowering the record magazine in exact timed relation with the movement of the selector elements and the selector restoring means.

A further object provides for an accurate

electro-mechanical means for stopping the movement of the record magazine and its associated selector elements when each record shelf is registered adjacent and parallel to the upper surface of the turntable.

Referring to the accompanying drawings:

Fig. 1 is a plan view of the entire machine in its repose position.

Fig. 2 is a side elevation of the mechanism.

Fig. 3 is a fragmentary plan view showing the transmission parts of the mechanism with the turntable, record transfer arms, and pickup carriage removed.

Fig. 4 is an end elevation taken through line a—a, Fig. 1.

Fig. 5 is an end elevation taken through line b—b, Fig. 3.

Fig. 6 is the side elevation taken through line c—c, Fig. 3.

Fig. 7 is an enlarged fragmentary elevation of the pickup carriage control mechanism.

Figs. 8 and 9 are sectional views of the pickup carriage operating mechanism taken through line d—d, Fig. 7.

Fig. 10 is an end elevation of the selector assembly taken through line e—e, Fig. 3.

Figs. 11, 12 and 13 show the transmission clutch and associated mechanism in their three different operating positions.

Fig. 4 is the schematic wiring diagram employed in the mechanism.

The plan view of the machine, Fig. 1, shows the principal components in their operative relation mounted on base 1. The electric driving motor 2 transmits power to the turntable 3 and the record changing components through the pulley 4, belt 5, pulley 6, pulley 7, belt 8, and pulley 9.

The pickup arm 10 is shown in its rest position and is pivotally mounted about vertical axis 11. The record magazine assembly 12 is retained and guided in its vertical movement by two vertical shafts 13, fixed to base 1.

The selector assembly 14 contains a series of selecting push buttons 15.

The record shifting arms 16 and 17 are pivoted about vertical axes 18 and 19, and arranged to swing horizontally to remove a selected record from the magazine and slide it upon the turntable for playing; and likewise upon the completion of playing, slide the record back from the turntable into its rest position on a shelf in the record magazine.

Stationary guide 20 is provided to insure the record being transferred to and from the turntable in its proper path.

Fig. 2 shows the motor and the belt drive system arranged to apply rotation to the turntable drive shaft 21, and the transmission drive shaft 22.

The pickup arm 10, Fig. 2, and its integral carriage 23, is pivoted upon horizontal axis 24 and is shown in rest or elevated position, the stylus end of the pickup arm being suspended against gravity by stud 25.

The record shelves 26, Fig. 2, are held in their spaced relationship by collars 27 and are clamped to the record magazine base 28 by three threaded tubular members 29 and hex. nuts 30, shown in Fig. 1. A portion of the peripheral edge of each record shelf 31, Figs. 1 and 6, adjacent to the turntable, is tapered to assure proper entrance of the record in the magazine when the record is being transferred.

The supports 32 and 33, Fig. 2, are integral with the base 1 and provide the bearings on which the record transfer arms 16 and 17 are pivoted on their axes 18 and 19, shown in Fig. 1.

Rotation is imparted to the turntable 3 through the elements shown in Fig. 3; namely, the pulley 6, shaft 21, and the friction clutch 34—35. When the clutch is engaged, the rotation is carried to shaft 36 and the worm 37. The worm wheel 38, which mates with the worm 37, is integral with the turntable quill shaft 39 and supported on suitable bearings. A pin 40 through the shaft 39 engages a slot in the hub of the turntable 3 and the drive is thus completed.

The collar 41, Fig. 3, is fixed to shaft 36 and a coiled spring 42 interposed between the said collar and the stationary bearing support for shaft 37. The spring thus urges the entire shaft toward the friction clutch. When the shaft is urged in this direction, the clutch is disengaged, and hence, rotation of shaft 21 does not rotate shaft 36 or the turntable.

The magnet 43, Fig. 3, cooperates with pivoted lever 44, one end of which is the magnet armature, and the opposite forked end engaging with the groove in collar 41. When the magnet 43 is energized, the pressure exerted by spring 42 is overcome and the shaft 36 and all its components are moved sufficiently to engage the clutch 34—35. Under these conditions, rotation of shaft 21 is carried to the turntable 3.

The record selecting and transferring mechanism is driven by transmission shaft 22, Fig. 3, which is rotated by the motor through the pulley and belt train previously described, and shown on Figs. 1 and 2.

The mitre gear 50, Fig. 3, is arranged to drive an identical gear 51 through an intermediate mitre gear 52. Clutch member 45 is keyed to the end of shaft 22 and arranged to be moved through a limited distance along the axis of its shaft. In the position shown on Fig. 3, the clutch member 45 is engaged with the selector clutch member 46. Clutch member 46 is fixed to shaft 47 which is supported on bearing supports 48 and 49. Attached to the end of shaft 47 is mitre gear 50. Thus, when clutch members 45 and 46 are engaged, rotation of shaft 22 rotates to mitre gear 50.

The mitre gears 50 and 51 being permanently meshed with intermediate mitre gear 52, mitre gear 51 is rotated in the opposite direction to that of mitre gear 50. The gear 51 transmits rotation to shaft 53, and the selector restoring drum 54, through worm 55 and worm wheel 56, which are permanently meshed.

Mounted over shaft 47 is commutator 57, Figs. 3 and 5. The contact arm 58, Fig. 3, is permanently geared to shaft 47, through worm 59 and worm wheel 60, shown on Fig. 5. The angular displacement of the commutator arm 58 is timed to have the identical angular displacement as the selector restoring drum 54.

Also mounted on shaft 47 is cam 61, Figs. 3 and 5, which makes and breaks contacts 62 and 63, once for every complete revolution of shaft 47.

The number of contacts 64 on the commutator 57 correspond identically with the number of selector restoring studs 65 and the number of record shelves in the record magazine, the relation of which will be hereinafter described.

Mitre gear 52, Fig. 3, is held in its rotational position by bearing supports 66, 67, and collar 68. The shaft 69 is slidably mounted in the bore of mitre gear 52, supports 66 and 67, and the collar 68. The shaft 69 is provided with both right and lefthand helical grooves along a portion of its length.

A flattened follower pin 70 is rotatably mounted in mitre gear 52 and arranged to engage the helical grooves in the shaft 69. Thus, when mitre gear 52 is rotated continuously in one direction the shaft 69, being restrained from rotation, will oscillate backward and forward through a range determined by the length of the helical grooves. The righthand groove is engaged with the follower pin 70 for the forward movement of the shaft, and the lefthand groove being engaged during the return movement of the shaft. The direction of the flattened follower pin for each movement is changed at the point where the two opposite grooves join each other at the end of their respective courses.

Wedge 71, Fig. 3, is guided for lateral sliding movement in ways 72 cut in the base 1, and affixed to shaft 69 by means of bracket 73. The wedge 71, Fig. 6, is shown in its withdrawn or retracted position with the record magazine in its lowermost position.

The record magazine assembly 12, Figs. 6 and 2, is shown resting by gravity on roller 74, which roller is mounted on the lower extremity of the record magazine base 28. Obviously, when the wedge 71 is advanced toward the record magazine, it will raise the entire magazine through a vertical path distances which are directly proportional to the movement of the wedge.

The record transfer clutch member 75, Fig. 3, is integral with worm 76, both elements floating on transmission drive shaft 22. The worm wheel 55 rotates about its vertical axis 78 and is permanently meshed with the worm 76. When the sliding clutch member 45 is shifted to the position shown in Fig. 11, rotation of the shaft 22 is imparted to worm wheel 77. A control cam 79, Fig. 2, is mounted on the upper surface of the worm wheel 77 and will be hereinafter described.

The record transfer crank pin 80, Fig. 11, protrudes from the upper surface of the cam 79 and provides reciprocating motion to the record transfer arms 16 and 17, Fig. 1, by means of link 84.

The vertical pivot shafts 18 and 19, Fig. 1, of the record transfer arms 16 and 17, carry cranks 81 and 82, which are connected together by adjustable tie rod 83. One end of the connecting link 84 is attached to the tie rod at pivot 85, and the opposite end attached to the crank pin 80. Thus, when the worm wheel 77 is rotated one-half revolution, the record transfer arms are swung from their respective positions on each side of the magazine to their transferred posi-

tions (dotted lines, Fig. 1) on each side of the turntable. (The arm 16, swings through any one of the spaces between adjacent record shelves in the magazine.) Obviously, continued rotation of the worm wheel 77 one-half revolution in the same direction will return the record transfer arms to their initial positions as shown on Fig. 1.

On the extreme end of each record transfer arm is mounted a yieldable grooved rubber disk 86 for the purpose of insuring a high friction contact to the edge of the record while it is being transferred.

The turntable spindle 87, Fig. 4, is pointed at the upper end and slidably arranged in the bore of the turntable quill shaft 39. Thus, the pointed end of the turntable spindle is below the surface of the turntable when the spindle is in its lowermost position.

The spindle 87, Fig. 4, is raised and lowered by the action of rocker arm 88 pivoted at screw 89, Figs. 4 and 3. The lower end of the spindle 87 is loosely attached to the forked end of the rocker 88. The opposite end of the same rocker 88 is in engageable relationship with cam 90, having on its underside a sharp incline 91. Cam 90 is fixed to the lower extended end of transfer arm pivot shaft 18. Thus as the record transfer arm 16, Fig. 1, nears the end of its motion when transferring a record, the sharply inclined surface 91, Fig. 4, of cam 90 engages rocker arm 88 and projects the turntable spindle into the central hole of the record, and by the action of the tapered point of the turntable spindle, the record is pulled into a position concentric with the turntable.

The pickup carriage pillar 92, Fig. 2, is permanently attached to the base 1. The pivot shaft 93 provides for the horizontal movement of the pickup carriage. The axis 11, Fig. 1, of this rotation, coincides with the axis of the pillar 92. Around the periphery of the pickup carriage pillar 92, Fig. 7, is slidably mounted the cylindrical raising and lowering cam 94.

Forked lever 95 is pivotally mounted at the upper end of the pillar and is provided with a projection extending downwardly.

Stud 25 is attached to a downward projecting arm 96 of the pickup carriage 23. In normal rest position, the stylus end of the pickup arm is held in raised position against the action of gravity by stud 25 bearing against lever 95, and the cylindrical cam 94.

Rod 97 is fixed to the cylindrical cam 94 and slidably passed through pivot block 98, which block is pivotally attached to tie rod 83. Obviously, when the rod 83, is reciprocated for transferring a record, the cylindrical cam rotates about the axis of the pillar 92, thus lowering the pickup arm and permitting the stylus to engage the starting grooves of the phonograph record. The pickup arm 10, Fig. 8, is moved by the playing of the record to a position shown by dotted lines on Fig. 9, about the axis 93. The flat spring 99, Fig. 8, fixed to the cylindrical cam 94, is provided for abutment with carriage projection 96 for returning the pickup arm and carriage to its normal position of rest, subsequent to the playing of the record.

Clutch member 45, Fig. 3, which alternately drives the selector and record transfer elements, is operated by bell crank 100, (pivoted on stud 101) spring 102, armature 103, spring 104 and cam follower lever 105. Lever 105 is pivoted on stud 106 and is urged into contact with cam 79, by spring 104 at the projection of the lever 75

105-a. Armature 103 is pivotally attached to the free end of lever 105, and said armature is urged away from the poles of electro-magnet 107 by saddle spring 108. When the machine is in its rest position, the armature 103 retains the long arm of the bell crank 100 in the position shown, Fig. 3, against the retrieving action of coil spring 102. In this position, it is obvious that clutch member 45 is engaged with the selector clutch member 46.

A circular slotted flange 109 is integrally attached with selector clutch member 46 and the number of radial slots around its periphery corresponds with the number of record shelves in the record magazine.

The short arm of the bell crank 100 is arranged to enter any one of said slots for the purpose of locking the selecting mechanism in proper selected position when the clutch member 45 is disengaged from member 46.

Link 110, Fig. 3, is pivotally mounted at one end of stud 111 and passes under the gears 76 and 77 and is urged against pin 112 protruding downwardly from the gear 77 by coil spring 113. The master switch restoring lever 114 is pivotally attached at the free end of link 110.

Fig. 4 shows a sectional view through the selector assembly 14 and illustrates one set of selector parts in their operative relationship. Manually operated push rod 115 is arranged to move selector lever 115 sufficiently far around its stationary pivot and against the restraining action of spring 116 to disengage the short arm of the selector bell crank 117, which bell crank is mounted on a stationary shaft 118. The spring 119 urges the short arm of the bell crank 117 in a downward direction. When the bell crank 117 is released from engagement with lever 115, the insulator 120, mounted on the long arm of the bell crank, closes electrical contacts 121-122.

Master switch release crank 123 pivoted about axis 123-a is common to all of the bell cranks 117, and is in the position shown, Fig. 4, when all the bell cranks 117 are in their restored or latched positions. When the bell crank 117 is released, the switch crank 123 is moved in a downward direction simultaneously with the long arm of the crank 117 closing contacts 121-122. Each bell crank 117 is arranged in the path of one of the studs 65 mounted on the selector restoring drum 54, Fig. 3. The number of helically arranged studs on drum 54 corresponds to the number of bell cranks 117.

Fig. 10 shows the master switch 124-125 being urged toward its closed position by spring 126. When the machine is in its rest position the switch arm 124 is engaged with abutment 114-a of the restoring lever 114. Integral with crank 123 is an elongated auxiliary crank 127 which is in operative contact with the lower edge of the lever 114. Obviously, when the crank 123 is moved downwardly by the action of any one of the bell cranks 117 the elongated member 127 will move upward and release the engagement between the master switch arm 124 and the abutment 114-a, thus closing the master switch contacts 124 and 125.

The electrical components of the machine are connected as shown in the schematic wiring diagram, Fig. 14. Electric power is supplied to the step-down transformer 128 from the power lines 133-134 and to the driving motor 2 through the master switch 124-125. One side of the secondary of the transformer 128 is connected to the "common" selector switch contacts 121 by con-

ductor 135, which conductor also feeds one side of the "cutoff" switch 130, and the turntable magnet 43. The opposite secondary terminal of the transformer 128 connects with one side of the clutch magnet 107 through conductor 136, and also connects the remaining side of the turntable magnet 43 through switch 131-132. Selector contacts 122 are connected to corresponding commutator contacts 64 by conductors 131.

Conductor 136 completes the circuit to magnet 107 through "cutoff" switch 129-130. The same circuit through magnet 107 is completed through conductor 138 through the make and break contacts 62-63 and the contact arm 58 of the commutator contacts 64.

The normally open "cutoff" switch 129-130 is closed by the action of the pickup carriage after completing the play of a record. The normally closed turntable magnet switch 131-132 is opened by the pickup carriage when the carriage 20 is in its rest position.

The operation of the mechanism will be described under the assumption that an operator has depressed one of the ten push buttons 15, shown in Fig. 1. Referring to Fig. 4, the forward movement of any push button 15 will move a corresponding latch 115 against the restraining action of spring 116, which permits bell crank 117 to be pulled into its selected position by the action of spring 119, as shown by dotted lines. 30 The movement of the bell crank simultaneously displaces crank 123 and closes one pair of contacts 121-122.

Referring to Fig. 10, the downward movement of the crank 123 raises the crank extension 127, which carries with it the free end of lever 114. The resulting upward movement of lever 114 disengages the switch arm 124 and permits the master switch 124-125 to close, thus starting the driving motor 2, Figs. 1 and 14.

During the selecting cycle, clutch member 45, Fig. 3, is engaged with its mating selector clutch member 46 and imparts rotation to shaft 47 and its associated components. The commutator arm 58 and the selector restoring drum 54 will rotate in timed relationship and simultaneously the magazine elevating shaft 69 will move horizontally, carrying with it wedge 71, Fig. 6, to raise or lower the magazine assembly 12. The direction of the movement of the wedge 71 is dependent upon which of the two helical grooves in shaft 69 is engaged with follower pin 70, shown in Fig. 3.

The make and break contacts 62-63, Fig. 3, are connected in series with the commutator 51, as shown in diagram, Fig. 14. When the commutator arm 58 is properly registered with a contact 64, corresponding with a closed selector contact 122, a circuit will be established through magnet 107. Cam 61 is accurately timed to close the make and break contacts 62-63 at a time when the upper surface of a selected record shelf, with its record lying thereon, is slightly above the surface of the turntable.

Just following the closing of the make and break contacts 62-63, and following the momentary closing of the circuit through magnet 107, a selector restoring stud 65, carried by drum 54, completes its mechanical engagement with its corresponding selector bell crank 117 by restoring it to its normal latched position in engagement with lever 115, as shown on Fig. 4. The selecting cycle is completed when the magnet 107 is momentarily energized, as shown in Fig. 11. The movement of the armature 103 releases 75

bell crank 100, permitting spring 102 to shift clutch member 45 into engagement with the record transfer clutch member 75. The short arm of the bell crank 100 engages a slot in flange 109 corresponding with the selected record, thus locking the record magazine in its proper elevated position, and simultaneously locking all other elements driven by selector clutch member 46.

The record transfer cycle begins when worm wheel 77 is rotated, as shown by arrow, Fig. 11, by means of worm 76, clutch members 75 and 45, and shaft 22. Pin 80, Fig. 11, imparts reciprocating motion to the record transfer arms 16 and 17 through a course shown by dotted lines, 15 Fig. 1, by means of connecting link 84, cranks 81, 82, and adjustable tie rod 83. Thus, when gear 77 is rotated 180 degrees the selected record is slid out of its position of rest onto the turntable by the movement of arm 17 and its friction disk 86. The distance between the edges of the two disks 86 is slightly greater than the diameter of the phonograph record. During the forward record transfer period, the cam 79 has likewise rotated 180 degrees, Fig. 12, and the cam follower lever 105 has retrieved the armature 103 against the restraining action of spring 104, sufficiently to re-engage the extreme end of the long arm of the bell crank 100. A slight further movement of cam 79 causes the elements to assume a position shown in Fig. 13, the clutch member 45 having been shifted to a neutral position when cam follower lever 105 passes over step x in the cam 79. Thus, the record is transferred to the turntable.

During the latter part of the movement of the record transfer arm 16, Fig. 4, cam 90 moves the short arm of rocker 88 rapidly in a downward direction, which movement projects the turntable spindle 87 through the central hole of the record.

The tapered point of the spindle causes the record to be brought into a position concentric with the turntable for rotation. Also, during the latter part of the movement of arm 16, the reproducer arm 10 is lowered, and its stylus is brought into playing contact with the starting groove of the record by the movement supplied by connecting link 83, Fig. 2. Fig. 7 shows the reproducer arm being held in its raised position with stud 25 resting against lever 95 and a portion of cam 94.

Fig. 9 shows connecting link 83 fully advanced in the direction shown by arrow. The peripheral portion of cam 94 has rotated sufficiently far to permit the projection 96 of the reproducer carriage to move inwardly toward axis 93, thus lowering the stylus end of the reproducer carriage. The lowering movement of the reproducer carriage closes the contacts 131-132, Fig. 14, and energizes the turntable magnet 43, Fig. 3. Thus, the armature 44 moves shaft 36 along its axis and engages the clutch 34-35 which imparts the rotation of shaft 21 to the turntable and the selected record thereon. The reproducer stylus, in playing the spiral groove of the record, will move the carriage 10 about vertical pivot 93 from a position shown in dotted lines, Fig. 8, to its "cutoff position," Fig. 9. At the finish of play, the reproducer arm closes contacts 129 and 130, Fig. 14, and again momentarily energizes magnet 107, which attracts armature 103, Fig. 13, and permits the re-engagement of clutch member 45 with its mating member 75, thus starting the rotation of worm wheel 77. The rotation of worm wheel 77, Fig. 3, and the action of pin 80 and its connecting link 88, starts the connecting

link 83, Fig. 9, to move in the direction opposite that shown by arrow, and results in the following functions, which occur substantially simultaneously.

First, the cylindrical cam 94, Fig. 7, moves between the pillar 92 and lever 95 to raise the stylus end of the reproducer arm. The raising of the reproducer arm opens the circuit through magnet 43, Fig. 14, by opening contacts 131—132. Thus, the spring 42, Fig. 3, releases the turntable clutch 34—35 and stops the rotation of the turntable.

Second; and simultaneously, the continued lateral movement of connecting link 83 retrieves the turntable spindle 87, Fig. 4, and moves lever 16, Fig. 1, to slide the record toward its position in the magazine. At the same time, spring 99, Fig. 9, comes into contact with projection 96 of the reproducer carriage and moves the reproducer arm about its pivot 93 toward its rest position shown in Fig. 8.

Rotation of gear 77 continues until arm 16 has slid the record back to its original position on its shelf in the record magazine and restores the reproducer arm to its normal starting position, shown in Fig. 1. This last 180 degree rotation of gear 77 likewise carries cam 79 through the same angular displacement. Cam follower lever 105 now assumes position shown in Fig. 3, and because armature 103 is engaged with bell crank 100, the clutch member 45 disengages from the transfer clutch member 75 and is forced into re-engagement with the selector clutch member. During the last part of the angular displacement of gear 77, Fig. 3, link 110 is moved by pin 112 sufficiently against the restraining action of spring 113 to cause lever 114, Fig. 10, to re-engage with the switch arm 124, thus opening the master switch 125—125, and stopping the entire mechanism.

It is obvious that in the event any other push button rods 15, Fig. 1, are manually depressed, the crank arm 127, Fig. 10 will be raised, thus preventing lever 114 from re-engaging the switch arm 124. Under these circumstances a complete repetition of the above described operations will occur in sequence until all the selected records corresponding to push buttons 15 have been played.

Having described our invention, we claim:

1. In an automatic record player adapted to plural selectivity, a stationary rotatable turntable, a reproducer mounted above and swingable over said turntable, a record magazine adjacent to said turntable having spaced record supports and capable of pre-determined reciprocal movement along the axis of the records contained therein, means for reciprocating the magazine, comprising a rotatable motor driven

gear, a shaft longitudinally movable within the bore of said gear having both right hand and left hand longitudinal helical grooves along a pre-determined portion of said shaft, said right hand and left hand grooves terminating in a common groove at each end of the shaft to form a continuous groove, a swingable lug within the bore of said gear projecting into the helical groove on said shaft, and means on said shaft connected with the magazine for reciprocating the magazine through its pre-determined course upon uni-directional rotation of said gear and longitudinal movement of the shaft.

2. In a plurally selective automatic record player, a stationary rotatable turntable, a reproducer mounted above and swingable over said turntable, a record magazine adjacent to said turntable having spaced record supports and capable of predetermined reciprocal movement along the axis of records contained therein, driven means cooperatively related with said magazine for reciprocating said magazine through a predetermined distance, a rotatable motor driven gear, a shaft longitudinally movable within the bore of said gear and cooperatively related to the said means, said shaft having both right and left-hand longitudinal helical grooves connecting each other at opposite ends to form a continuous groove along a predetermined portion of the length of said shaft, a swingable lug within the bore of said gear projecting into the helical groove on said shaft, and means on said shaft connected with the magazine for reciprocating the magazine through a predetermined course upon the uni-directional rotation of the said gear and longitudinal movement of the shaft.

3. In a plurally selective automatic record player, a record magazine having spaced record supports and arranged for predetermined reciprocal movement along the axis of the records contained therein, a power transmission shaft adapted for uni-directional rotation, reciprocating means for reciprocating said magazine through a predetermined course, gear means adapted to be rotated by said shaft, a second shaft cooperatively related with the said reciprocating means having endless right and left-hand helical grooves along a predetermined portion of its length, said second shaft adapted to reciprocate along its grooved length upon rotation of said gear means, a selector restoring device geared to said first-mentioned shaft and arranged to be rotated thereby, said record magazine and said selector restoring device adapted to move equal proportional increments upon the uni-directional rotation of the first said shaft.
